[57] CLAIM

The ornamental design for an armoire, as shown and described.

DESCRIPTION

FIG. 1 is a front perspective view of an armoire showing my new design;

FIG. 2 is a right side elevational view, the left side being a mirror image thereof; and,

FIG. 3 is a front elevational view thereof.

The top, bottom and rear of the armoire not shown in the drawing or described in the specification form no part of the claimed design.
